DESIGN FOR A DISPLAY TABLE

Anthony Di Simone, Corona, N. Y.

Application November 17, 1938, Serial No. 81,158

Term of patent 14 years

To all whom it may concern:

Be it known that I, Anthony Di Simone, a citizen of the United States of America, residing in Corona, in the Borough of Queens, county of Queens, and State of New York, have invented a new, original, and ornamental Design for a Display Table, of which the following is a specification, reference being had to the accompanying drawings, forming part thereof, wherein:

I claim:

The ornamental design for a display table, substantially as shown.

ANTHONY DI SIMONE.
